APPARATUS FOR OPERATING UPON HEELS

Abraham Madow, Brookline, Mass., assignor to
United Shoe Machinery Corporation, Borough
of Flemington, N. J., a corporation of New
Jersey

Application February 9, 1938, Serial No. 189,555

5 Claims. (Cl. 51—94)

My invention relates to apparatus by which there may be performed upon heels such an operation as that of squaring, this involving the production upon the periphery of a heel of a surface, which, considered at an intersecting horizontal plane, is bounded by a straight line, though curved vertically.

In squaring a heel, the usual practice is to subject the peripheral wall, as at the rear, to the action of a rotary abrading member, such as a scouring roll, which will remove the heel-material to the desired depth from a line extending transversely of the tread-surface to a point somewhat below the edge of the heel-cup and thereafter to finish the surface upon another abrading member, as a buffing roll. It is convenient to perform these operations after the heel has been attached to a shoe. An object of my invention is to effect the squaring of the heel quickly and accurately by means which is convenient for the operator to use and which may be adjusted readily to meet different work-conditions.

In the accomplishment of this object, I combine with a roll having a scouring surface and a buffing surface a support or jack adapted to enter and hold a shoe for the presentation of the back of its heel to the abrading means and a mounting for the support comprising a pair of spaced arms pivoted upon the frame and connected by a rod, the support being movable along and about the axis of the rod. The first movement is to determine the abrading section with which the work is to contact for scouring or buffing as desired, and the second permits such contact. In the form of the invention herein disclosed, the rod is rotatable upon the mounting-arms, the shoe-supporting jack being splined to the rod to move longitudinally of while turning with it. An arm is fast upon the rod for engagement with a stop which limits the depth to which the abrading action may take place.

In the accompanying drawing,

Fig. 1 is a top plan view of the apparatus;

Fig. 2, a side elevation looking from the right

45 in Fig. 1;

Fig. 3, a sectional detail of the connection between the jack and its carrier-rod, it being taken along the line III—III of Fig. 2, while

Fig. 4 shows in perspective an example of the 50 work performed by this apparatus.

At 10 appears a portion of a machine-frame, with which is associated a support, appearing in the present instance as spaced brackets 12, 12 projecting horizontally from the frame. These 55 brackets, with the elements they carry, may be

adjusted together vertically by virtue of a slot-and-screw connection 14 to the frame and elevating screws 16 threaded through frame-lugs and upon which the brackets rest. Rotatable in bearings at the top of the frame is a horizontal shaft 18, upon which is fast an extended roll or cylinder 20. Side by side upon the roll are abrading sections 22 and 24, the first of which may be coarse, while the second is relatively fine. That is, the section 22 is adapted to rapidly reduce or scour work presented to it, while the section 24 will finish or buff the surface produced by the companion section. The circumference of the roll will be chosen to give the correct curvature to the surface which the sections produce. Said roll may be rotated at the chosen speed by belt or other gearing 25. At the outer extremity of each bracket 12, a vertical plate 26 is secured, this having extending toward the abrading means, a slot 28, the slots in the two plates being 10 horizontally aligned. Pivoted to each plate by a bolt 30 passing through the slot is an arm 32, the inner end of which is held against lateral displacement by a post 34, rising from the bracket and provided with a vertical guide slot 15 36 through which the arm may be moved. Each arm 32, at its lower edge, has an inward extension 38, so this portion of said arm is L-shaped in transverse section. In addition to stiffening 20 the arm, the extension supports it for angular 25 adjustment about the pivot-bolt 30. Rising from each bracket through a slot 39 in the corresponding arm-extension 38 is a post 40 threaded at its upper end. Washers 42, 42 encircle the post 30 upon opposite sides of the extension. Between 35 the bracket and the lower washer, a spring 44 is interposed, this urging up the arm to a variable extent determined by the adjustment of a nut 46 upon the threaded end of the post. By the 40 means just indicated, the arms and the elements 45 which they carry may be adjusted both bodily and angularly with respect to the roll 20.

Between the two arms 32, 32 is mounted a shoe-supporting member or jack 48 arranged to hold a shoe with the tread surface of the heel substantially parallel to the axis of the roll 20. The jack 48 is carried by a rod 50 extending from arm to arm and being substantially parallel to the axis of the roll 20. This rod may turn in bosses 52 projecting inwardly from the arms. It 50 is held in the arms 32 against longitudinal displacement by the hub of an arm 54 fast upon one end of the rod and a collar 56 secured to the other, each of these elements contacting with the outer side of the adjacent arm. The direct 55

mounting of the jack is furnished by a downward projection 58 from it, this terminating in a laterally extending sleeve 60 slidable longitudinally of the rod but being compelled to turn with it by 5 a connecting feather 62 movable in a spline 64 in the rod. This movement of the jack along the rod permits it to present work mounted upon it to either of the abrading surfaces 22, 24, while rotation of the rod and jack together allows the 10 latter to be moved from a work-receiving position, spaced from the roll 20, to an operating position in which the supported work may be subjected to the action of the abrading surfaces. The distance through which the jack may be 15 moved in either direction is limited by one of two stop-screws 66 and 68, threaded through lugs upon one of the arms 32 and with which the arm 54 may contact. When the arm is against the screw 66, the weight of the jack will 20 hold it away from the abrading means, giving sufficient space to place the work upon the jack without danger of contact with the surfaces 22, 24. When the mounting is swung inwardly, the rod 50 turning in its bearings, the work upon 25 the jack may be brought into engagement with either of the abrading surfaces, and this caused to act to a depth approximately determined by the screw 68.

In using the apparatus, and with the arm 54 30 of the jack-mounting engaging the screw 66 and the jack 48 opposite the scouring surface 22 of the roll 20, the operator places the shoe, shown at S with its heel H, upon the jack, drawing the counter-portion of said shoe against the rear of 35 the jack. The opposite extension of the jack at the rear and front of the mounting-projection 58, bearing against the interior of the shoe, gives an approximately correct transverse angular position for the work. The jack is then tipped forward, the rod 50 turning in the arms 32, until the back of the heel strikes the rotating surface 22. This will remove the heel-material, producing a depression transversely squared but curved vertically in a form determined by the circumference 40 of the roll and having a depth which will not be greater than the limit fixed by the engagement of the arm 54 with the stop-screw 68. Since the portion of the work operated upon is placed by its inverted position directly in the view of the 45 operator, he is able to watch the action of the scouring surface and swing the jack away from the roll when approximately the desired depth has been attained. Then, the jack is carried to the left along the rod opposite the buffing surface 50 24 and again swung inwardly, so the area squared by the surface 22 may be smoothed. This buffing action may continue, until the stop-screw 68 prevents further reduction. The work, having the finished form shown in Fig. 4, will be removed 55 from the jack, which is shifted to the right ready for the presentation of another heel to the abrading surfaces. By a proper combination of adjustments of the arms 32 bodily toward and from

the roll 20 by varying the pivot-points at 30 and angularly about the pivots under the influence of the nut 46 and the spring 44, the relation which the produced surface a bears at b to the rear of the heel-cup and at c to the tread-surface 5 may be varied within the desired limits.

Having described my invention, what I claim as new and desire to secure by Letters Patent of the United States is:

1. In combination, a rotatable abrading roll, 10 a pair of arms spaced from each other, a pivotal support for each of said arms, a member connecting the arms and having an axis substantially parallel to the axis of the roll and spaced a substantial distance from the periphery of the 15 roll, a shoe-support formed and arranged to enter a shoe and mounted to turn about the axis of the connecting member to present a supported shoe to the abrading member or to remove it therefrom, said arms being adjustable about 20 said pivotal supports to vary the locality on the shoe which is to engage said roll, and means for maintaining said arms in adjusted position.

2. In a machine for squaring heels, the combination with a frame, of a roll rotatable thereon and provided with a scouring surface and a buffing surface, spaced arms pivoted upon the frame, a rod connecting the arms, and a jack supported by the rod and arranged to turn about the axis of said rod and to move longitudinally 25 thereof for the presentation of a jacked shoe to either the scouring surface or the buffing surface.

3. In a machine for squaring heels, the combination with a frame, of a roll rotatable thereon and provided with a scouring surface and a buffing surface, spaced arms pivoted upon the frame, means arranged to hold the pivots of the arms in different positions upon the frame, means arranged to vary the angular relation of the arms, and a jack supported by the rod and arranged 35 to turn about the axis of said rod and to move longitudinally thereof for the presentation of a jacked shoe to either the scouring surface or the buffing surface.

4. In a machine for squaring heels, the combination with a frame, of a roll rotatable thereon and provided with a scouring surface and a buffing surface, a rod rotatable upon the frame substantially parallel to the axis of the roll, and a jack splined to the rod to turn and move longitudinally thereof.

5. In a machine for squaring heels, the combination with a frame, of a roll rotatable thereon and provided with a scouring surface and a buffing surface, a mounting member carried by 55 the frame, a rod rotatable upon the mounting member substantially parallel to the axis of the roll, a jack splined to the rod to turn and move longitudinally thereof, an arm fast upon the rod, and a stop variable in position upon the mounting member and arranged to receive contact of the arm.

ABRAHAM MADOW.
